UNITED STATES PATENT OFFICE.

GEORGE W. FIELDHOUSE, OF OAK PARK, ILLINOIS.

APPARATUS FOR MAKING TWYERS.

No. 898,348.

Specification of Letters Patent.

Patented Sept. 8, 1908.

Application filed April 30, 1908. Serial No. 430,079.

To all whom it may concern:

Be it known that I, GEORGE W. FIELDHOUSE, of Oak Park, Cook county, Illinois, have invented a new and useful Apparatus 5 for Making Twyers, of which the following is a full, clear, and exact description, reference being had to the accompanying drawings, forming part of this specification, in which—

Figure 1 is a vertical section showing the 10 core box in which the central core for the twyer is formed. Fig. 2 is a vertical section showing the core box in which the shell core for the twyer is formed and showing the vent pipes as they are held in position while the 15 sand is being rammed in the core box to form the cores. Fig. 3 is a plan view showing the adjustable mechanism by which the vent pipes are held in position relatively to each other and to the center of the core-forming 20 apparatus. Fig. 4 is a plan view of the stripper, the top half of the view showing the drag and bottom plate in their inverted position upon the stripper, the drag and bottom plate being removed in the lower half of this view. 25 Fig. 5 is a vertical section on the line V—V of Fig. 4 showing the drag which has been rammed and with the inverted bottom plate in place on the drag, the bottom plate together with the drag being in readiness to be 30 removed from the stripper. Fig. 6 is a vertical section of the stripper on the line VI—VI of Fig. 4, the drag and bottom plate being omitted. Fig. 7 is a vertical sectional view 35 of the cope which has been rammed with sand, and showing the pattern for the nose of the twyer in position in the cope. Fig. 8 is a vertical sectional view on the line VIII—VIII of Fig. 9 showing the drag, cheek and cope assembled together to form the flask, 40 and showing the shell core held in position in the flask in accordance with my invention. Fig. 9 is a top plan view of the assembled flask shown in Fig. 8. Fig. 10 is a detail view showing the means employed in securing 45 the vent pipes to the pipe clamps when the parts are assembled in place in the flask. Fig. 11 is a perspective view showing a detail of the pipe clamp used in securing the vent pipes in place in the drag of the mold. Fig. 50 Fig. 12 is a detail plan view of the adjustable slides on the stripper on which the pipe clamps are placed while the drag is being rammed with sand.

My invention relates to the molding of

twyers, twyer coolers, and similar articles, in 55 which fluid metal is cast around a shell core, and is designed to provide improved means for making such castings, for making and securing the cores in place in the flask, which will reduce the amount of chipping necessary, 60 and to provide a simple and effective apparatus by which the output of cores and of cast twyers is largely increased without increase in the cost of making such twyers.

The invention is further designed to provide an improved apparatus, which is adapted 65 for use in making twyers of various sizes and shapes, and in the use of which the equipment of flasks necessary to make a variety of sizes of such castings is largely reduced.

In the drawings, referring to Fig. 1, 2 represents the core box, in which the central core B is formed. The box 2 is mounted upon a bottom plate 3, the bottom plate and box having coacting shoulders by which the 75 box is centered on this plate. A lifting plate 4 by which the core is handled in removing it from the core box, is placed within the annular opening in the bottom plate 3. The lifting plate 4 is provided with a recessed 80 slot, in which the T-head of the lifting rod 5 is removably secured. Surrounding the lifting rod 5 is the pipe 6, which forms the central vent for the central core.

Referring to Fig. 2, 7 is the base of the core 85 centering machine, on which the shell core A of the apparatus is formed. The base 7 is provided with adjustable slides 8 and 9, by which the vent pipes 10 are secured in place in their proper position in the core box 11. 90 The lower end of each of the pipes 10 is provided with a transverse opening or hole, through which a suitable pin 12 is inserted, this pin engaging with recesses or grooves in the slides 8 and 9 to hold the pipes 10 in position while the core is being rammed. The slides 9 are connected by means of links 13 with a disk 14 to enable the slides 9 to be advanced and retracted simultaneously when the disk 14 is turned by the operator. Each 100 of the slides 8 and 9 is provided with a thumb-screw 15, by which the disks are locked in the desired position.

In constructing shell cores of different diameters, the blocks 8 and 9 are adjusted to 105 the desired diameter, and are secured in their adjusted position by means of the thumb-screws 15. On the top of the base 7 is a core

plate 16 having suitable slots through which the slides 8 and 9 project.

The core box 11 is provided with an annular recess on its bottom end, which by engagement with the periphery of the core plate 16 accurately centers the core box in place on its plate and on the base 7. A removable pattern 17 for the core box 11 is then placed on the core plate 16. The pipes 10 are successively held at their top ends by the operator, while the bottom portion of the core is being formed by ramming the sand in the core box. After a small portion of the core has been formed the sand will hold the pipes 15 in the proper position while the remainder of the core is being formed. A swinging arm 18 is pivotally secured to the core box 17 by means of a pin 18'; and the outer end of the arm 18 is provided with an adjustable filletting tool 19, by which the shell core is rounded off to the desired radius on its outer upper edge.

Referring to Figs. 4, 5 and 6, 20 represents the base of the stripper. This stripper is 25 provided with radial slots, in which slides 21 are secured so as to be adjustable radially. The slides 21 are connected by means of links 22 with a disk 23, which is mounted upon the stub shaft 24 secured to the base 20. The disk 23 is provided with a handle 25, by which the slides 21 are advanced and retracted toward and away from the center of the stripper in adjusting the slides to the desired position for twyers of different sizes. 30 On the slides 21 and projecting above the surface of the base 20 are centering holders 29 on which the pipe clamps 30 are placed. After the slides 21 have been adjusted to the desired position relative to the center of the 35 stripper, a pipe clamp 30 is placed upon each of the centering holders. The drag 26 is then rammed after it has been placed on top of the base 20, and a bottom plate 27 is then placed upon its upper surface. The drag is 40 then in readiness to be inverted and be removed from the stripper. Dowel pins 28 are provided on the stripper which engage with suitable ears on the drag so as to center the drag and permit it to be rammed with 45 sand with the pipe clamps in the desired position.

Twyers of different sizes will have noses having fillets of different radii. For that reason a removable nose pattern 31 is secured to the bottom plate 31^a by means of the pin 31^b. The cope is then placed in position upon the bottom plate 31^a and is then rammed with sand. A plug 32 placed in position centrally in the cope forms the vent in 50 the cope. After the cheek has been rammed and the pattern for the twyer in the usual well-known manner, which need not be further described, the drag, the cheek and the cope, are assembled together as shown in 55 Figs. 8 and 9. In assembling these parts to-

gether, the shell core A is first secured in place on the drag 26 by means of the pipes, which are secured to the pipe clamps on the drag by pins 33 and 34, as shown in detail in Fig. 10. The cheek is then placed in position 70 on top of the drag, and the central core B is placed in position in the cheek and on top of the drag. The cope is then placed on top of the cheek, the dowel pins and registering opening in the ears on the cheek, drag, and 75 cope, insuring that the parts come in proper alignment. The apparatus is then in readiness to cast the twyer.

The advantages of my invention result from the manner of securing the vent pipes, 80 while ramming the shell core of the twyer, from the use of the pipe clamps and the pins for securing the pipes to the clamp, and from the use of the improved stripper in which shell cores of various diameters and sizes may 85 be made with the same stripper instead of providing a separate stripper for the shell cores used with each size of twyer.

Instead of securing the vent pipes by 90 means of threaded nuts to a shell plate and center plate, the shell plate and center plate are dispensed with and the core is accurately placed in position in the mold and insures an equal thickness of metal in the shell in the wall of the twyer. The time required in adjusting the cores when the threaded nuts are 95 employed for securing the shell core in the mold is greatly reduced by the use of my improved apparatus, and the use of wires for securing the shell core by means of the vent 100 pipes in position in the assembled mold, is also rendered unnecessary.

Variations in the construction and arrangement of the parts may be made without departing from my invention.

I claim:

1. In apparatus for molding, a stripping member having a plurality of radially adjustable anchor supports; substantially as described.

2. In apparatus for molding, a drag mold stripper plate having a plurality of radially adjustable supports, a core centering device, also having a plurality of radially adjustable supports, and means for adjusting the two 115 sets of supports to corresponding positions; substantially as described.

3. In apparatus for molding, a drag mold stripper plate having a plurality of radially adjustable supports, a core centering device, 120 also having a plurality of radially adjustable supports, means for adjusting the two sets of supports to corresponding positions, and means for securing said supports in their adjusted positions; substantially as described.

4. In apparatus for molding, a drag mold stripper having a plurality of radially adjustable clamp supports, a core centering device, having a plurality of radially adjustable vent pipe supports, means for adjusting the two 130

sets of supports to corresponding positions, and means for locking the supports in their adjusted positions; substantially as described.

5. In apparatus for molding, a drag mold having a clamp for anchoring the core embedded in the said drag; substantially as described.

In testimony whereof, I have hereunto set my hand.

GEORGE W. FIELDHOUSE.
